UNITED STATES PATENT OFFICE.

ROSS W. MORRISON, OF WASHINGTON, DISTRICT OF COLUMBIA.

CONCRETE-FORM HOLDER.

Application filed February 9, 1925. Serial No. 7,990.

To all whom it may concern:

Be it known that Ross W. MORRISON, a citizen of the United States of America, residing at Washington, District of Columbia, 5 has invented certain new and useful Improvements in Concrete-Form Holders, of which the following is a specification.

My invention relates to improvements in tying apparatus and is particularly adapted to that type of element used for reinforcing and binding concrete forms.

The object of my invention is to provide an apparatus of the class described so constructed that it may be easily applied to 15 any form and may be employed for use from one job to another.

A further object of my invention is to provide means for operating the tying element and at the same time locking the same 20 in a secured position around a form.

In the accompanying drawings:

Figure 1 is a side elevation of a form for a concrete column having my improved means applied thereon;

25 Figure 2 is a sectional view taken on the line 2—2 of Figure 1;

Figure 3 is an enlarged detail view of the tying element;

30 Figure 4 is a sectional view taken on the line 4—4 of Figure 3, and

Figure 5 is a detail view showing a modified form of the locking element.

In the following description I have disclosed my invention as being applied to a 35 vertical column form, the same being made of suitable lumber and comprising boards A secured together by a retaining band B and braced by uprights C. It is to any one of these uprights C that I apply my tying 40 apparatus.

Referring to the accompanying drawings in detail wherein like reference numerals 45 denote corresponding parts throughout the several views, the letter D indicates a main member of the tying apparatus, the same comprising a U-shaped member having a base 1 and legs 2 which is formed of a suitable metallic bar of suitable gauge to stand the strain to be applied thereto, or if desired, the member D may be a casting.

The intermediate portion of the base 1, of the member D, has rotatably mounted therein a stub shaft or bolt 3 which passes 50 through a suitable opening formed in the base 1. That portion of the bolt 3 adjacent its head is cylindrical in form and is

provided with spaced openings 4 and 5, the purpose of which will be hereinafter described. The remaining portion of the bolt 3, is squared, as indicated at 6 and a portion 60 adjacent its end is reduced and rounded as indicated at 7. The extreme end portion of the bolt remains squared and is provided with an opening 8 through which a locking element 9 passes, the purpose of which will 65 be apparent as the description proceeds.

Slidable upon the squared portion of the bolt 3, and retained therein by the locking element 9, is a second U-shaped member E the base portion of which is provided with 70 a squared opening to receive therein the squared portion 6 of the bolt 3. The base of the member E is slightly longer than that of the member D, so as to permit the member E to embrace the member D, as disclosed 75 in Figure 2.

The openings 4 and 5 provided in the bolt 3, receive therein the end portions of a wire 10 which surrounds the form and so connected to the bolt 3 that upon rotation 80 of the latter, the wire 10, will be drawn tightly around the form.

In the operation of the device the wire 10 is placed around a form and the member D is positioned over the uprights C of the 85 form as indicated in Figure 2. In the initial positioning of the device upon the form the U-shaped member E is drawn back to a position so that it may rotate without striking the member D, and during the rotation, by 90 reason of the squared connection with the bolt 3, the latter is caused to rotate thus winding the wire 10 around the cylindrical portion of the bolt. After the wire 10 has been drawn tightly around the form the member E is moved inwardly upon the squared portion of the bolt 3, until it embraces the member D as illustrated in Figure 2, thus locking the bolt and preventing 95 the same from rotation.

In removing the tying apparatus from a form, the member D is slid backwardly upon the bolt 3, until its squared opening provided in its base lies within the reduced portion 7, at which time the bolt 3 will be free to rotate under influence of the strain or pull thereon by the end portions of the wire 10. If desired, a suitable wrench or the common claw bar may be applied to the squared portions of the bolt 3 to assist in rotating the 105 same.

It may be further desired to remove the

tying element without rotating the bolt, and to accomplish this it is only necessary to clip the wire 10 adjacent its connections with the bolt 3.

5 In some instances where the width of the timbers used is equivalent to the space between the legs of the member D, thereby preventing the members from assuming an inclined position as disclosed in Figure 1, it

10 is my further object, as disclosed in Figure 5, to provide the legs of the member E with slots 11, to receive therein the wire 10 when the member E is moved inwardly to prevent rotation of the bolt.

15 From the foregoing description it is apparent that I have described my invention as being applied to a form constructed for the molding of a column but as will be apparent to those skilled in the art, the tying apparatus may be used in any form of concrete work where it is desired to reinforce the form externally and prevent the same from breaking under the pressure of the concrete poured therein.

20 25 What I claim as my invention is:

1. In a tying apparatus of the class described, the combination of a form engaging member and a rotatable member carried thereby, form embracing means secured to 30 the rotatable member, and a member movable upon said rotatable member and adapted to engage the form engaging member for preventing the rotation of the rotatable member.

35 2. In a tying apparatus of the class described, the combination of a form engaging member and a rotatable member carried thereby, form embracing means secured to said rotatable member and drawn 40 tightly thereabout upon the rotation of said rotatable member, and a member slidale upon said rotatable member and engageable with the form engaging member for rotating and preventing the rotation of the rotatable member.

45 3. In a tying apparatus of the class described, a form engaging member having a rotatable member mounted therein, a flexible element embracing a form and having 50 its ends connected to said rotatable member whereby rotation of the latter will draw said flexible element about a form, and a member slidale upon said rotatable member and adapted to embrace the form engaging member to prevent the rotation of the rotatable member.

55 4. In a tying apparatus of the class de-

scribed, a form engaging member having a rotatable member carried thereby, said rotatable member being provided with a 60 squared portion, form embracing means secured to said rotatable member and adapted to be wound thereon, and a member slidale upon the squared portion of the rotatable member for rotating the same and locking it against rotation.

5 In a tying apparatus of the class described, a form engaging member having a rotatable member carried thereby, said rotatable member being provided with a 70 squared portion, form embracing means secured to said rotatable member and adapted to be wound thereon, and a member slidale upon the squared portion of the rotatable member for rotating the same and embracing the form engaging member for locking the rotatable member against rotation.

6. In a tying device of the class described, a form engaging element having carried thereby a rotatable member, said member being provided with a squared portion, form embracing means secured to said rotatable member, a second element engageable with the squared portion of the rotatable member for rotating the same, and said second element adapted to slide upon said rotatable member to embrace said form engaging element for preventing the rotation of the rotatable element.

7. In a tying apparatus of the class described, the combination of a form engaging member and a rotatable member carried thereby, form embracing means secured to the rotatable member, and a member movable longitudinally upon said rotatable member and engageable with the form engaging member for preventing the rotation of the rotatable member.

8. In a tying apparatus of the class described, the combination of a form engaging member and a rotatable member carried thereby, form embracing means secured to the rotatable member, and a member slidale longitudinally upon said rotatable member and engageable with the form engaging member for rotating and preventing the rotation of the rotatable member.

In testimony whereof I affix my signature in presence of a witness.

ROSS W. MORRISON.

Witness:

CATHARINE S. WILTON.
